UNITED STATES PATENT OFFICE.

LOGAN L. MALLARD, OF ATLANTA, GEORGIA, ASSIGNOR TO PARAGON SUSPENDER CO., OF ATLANTA, GEORGIA, A CORPORATION OF GEORGIA.

BELT-BUCKLE.

No. 912,865.

Specification of Letters Patent.

Patented Feb. 16, 1909.

Application filed December 17, 1907. Serial No. 406,904.

To all whom it may concern:

Be it known that I, LOGAN L. MALLARD, a citizen of the United States, residing at Atlanta, in the county of Fulton and State of Georgia, have invented new and useful Improvements in Belt-Buckles, of which the following is a specification.

This invention relates to belt buckles, and particularly to devices of this class for personal wear, and consists in the construction and arrangement of the several parts which will be more fully hereinafter specified.

The primary object of the invention is to provide a belt and buckle assembly of such nature that the belt may be readily attached to and disconnected from the buckle to facilitate the use of different colors or styles of belts with the same buckle, and to avoid sewing or the use of other fastening means to secure the belt to the buckle and consequently save considerable time and annoyance in reliably fastening a buckle to a belt or in effecting a release of the said parts.

In the drawing: Figure 1 is a perspective view of one form of buckle embodying a part of the features of the invention and shown open. Fig. 2 is a longitudinal vertical section through the buckle shown by Fig. 1 and illustrated as being closed. Fig. 3 is a perspective view of the belt and buckle shown assembled and the securing means for the belt illustrated as open. Fig. 4 is a bottom plan view of the buckle and a portion of the belt. Fig. 5 is a longitudinal vertical section through the belt and buckle, as shown by Fig. 4. Fig. 6 is a perspective view of a modified form of buckle. Fig. 7 is a longitudinal vertical section through the buckle shown by Fig. 6.

Similar characters of reference are employed to indicate corresponding parts in the views.

Referring to Figs. 1, 2, 3, 4 and 5, the numeral 1 designates a buckle frame which is preferably of rectangular form and provided with an intermediate fulcrum cross bar 2 in which is movably fitted the fulcrum head or member 3 of the tongue 4. The rear extremity of the buckle frame 1 up to the fulcrum cross bar 2 has a closed plate 5 fixed thereto and forms with a movable clamping member 6 fulcrumed to the rear end of the frame 1 a securing box or inclosure for the end of the belt 7. The clamping member 6 is also in the main in the form of a closed

plate, and adjacent its connection with the rear ends of the frame 1 is provided with an angular securing flange 8, having the free edge 9 serrated or otherwise constructed to firmly engage the belt. The opposite or forward extremity of the clamping member has an angular locking tongue 10 integrally formed therewith and concaved to spring or snap around the rear portion of the fulcrum cross bar 2. As shown by Fig. 2, the clamping member 6 when closed forms a tight joint with the portion of the buckle with which it coöperates, and when the locking tongue 10 is forced into engagement with the rear portion of the fulcrum cross bar 2, the said clamping member will be prevented from becoming accidentally disengaged. The locking flange 8 of the clamping member 6, when the latter is closed, has a slight rearward inclination, as shown by Fig. 2, to insure a reliable engagement thereof with the portion of the belt 11 enclosed within the rear box-like extremity of the buckle.

The buckle shown by Figs. 1, 2, 3, 4 and 5 is a rigid construction or does not have swinging movement on the end of the belt when applied to the latter. The buckle shown by Figs. 6 and 7, however, illustrates a rear box-like belt securing structure 11, provided with a locking member 12, similar to the member 6, and having knuckles 13 at the forward extremity in which the rear bar 14 of a buckle frame 15 is hinged or movably mounted, and between the knuckles a buckle tongue 16 is also movably disposed to coöperate with the frame 15. The knuckles 13 in this instance constitute a fulcrum cross bar, and the locking member 12 has a concaved locking tongue 17 at its front extremity to engage the knuckles 13, the said locking tongue 17 having a central slot 18 to permit the movably attached end of the tongue 16 to clear the central portion of the said tongue 17. The rear extremity of the locking member 12 has a locking flange 18' in all respects similar to the flange 8 heretofore described.

The belt shown by Figs. 3, 4 and 5 has a billet or retaining loop 19 secured thereto at a suitable distance from the attached end thereof to receive the loose end of said belt after attachment to the buckle. In the form of buckle shown by Figs. 6 and 7 a billet or retaining loop 20 is secured to the rear extremity of the box-like device 11, the

latter having a cross bar 21 with spurs 22 integrally formed with its opposite side edges and bent upwardly over and driven into the adjacent portion of the said billet or retaining loop 20.

From the foregoing it will be seen that the belt and buckle embodying the features of the invention have the advantages of ready separation and assemblage without resorting to the usual inconvenient and tedious methods.

Two forms of buckles have been illustrated, one showing a rigid structure and the other embodying a movable buckle proper. By thus disclosing the invention, it is intended to be understood that any form of buckle may be used, so long as the attaching feature, which is similar in both forms of the buckle shown, is employed.

This form of buckle attaching means is particularly well adapted for use with a belt having size markings or indications thereon, in view of the fact that when the end of the belt is inserted and secured in the box-like structure at the rear extremity of the buckle, the size desired can be more readily obtained with accuracy and without requiring any part of the end of the belt, which is secured in the buckle, to be bent around or doubled over the securing bar or analogous device. On the contrary the cut end of the belt is abutted close against the rear portion of the fulcrum cross bar of the buckle adjacent to the rear terminal of the buckle tongue 4 or 16.

Any form of belt may be used and different colors or styles of belts may be also attached to a single buckle equipped with the securing means set forth. Furthermore, if a belt after continued use becomes strained or weakened at the extremity engaged by the box-like securing and inclosing means at the rear end

of the buckle, it would entail but a simple operation to cut off the said extremity of the belt and cause the buckle to engage the new and stronger portion of the belt.

Many other advantages will appear from time to time to those using the belt and buckle embodying the features of this invention.

Having thus described the invention, what is claimed, is:

A buckle having a box-like securing means at the rear extremity comprising a flat rigid side immovably secured to the members of the buckle frame and having side flanges and a movable member which closes in parallel relation to said side, the movable member being hinged at its rear extremity to the rear extremity of the said flanges of the flat rigid side and having projecting means at its hinged and free extremities that extend inwardly towards the said rigid side, the one projecting means engaging a portion of the buckle to hold the movable member closed over the flat rigid side, and a belt having one extremity removably inserted in the box-like securing means under the rear hinged extremity of the movable member and held flat against the said rigid side by the projecting means at the hinged extremity of the movable member, the front extremity of the buckle being provided with a tongue for detachable engagement by the free extremity of the belt.

In testimony whereof I have hereunto set my hand in presence of two subscribing witnesses.

LOGAN L. MALLARD.
